KNITTING MACHINE AND NEEDLE
THEREFOR

Alvin Schwartz, New York, N. Y.

Application September 10, 1945, Serial No. 615,270

8 Claims. (Cl. 66—86)

1

This invention relates to warp knitting machines and to needles therefor.

The primary object of the present invention is to provide in or for a warp knitting machine a spring-beard needle constructed and arranged so that the closing of the beard of the needle in the casting-off operation is effected by the tension of the thread on the needle during the operation of the knitting machine, with the result that the presser bar for closing the beard of the needle can be eliminated while at the same time enabling the production of knit fabrics having the desirable characteristics of knit fabrics produced by spring-beard needles.

It will be understood that the elimination of the presser bar also results in the elimination of the actuating mechanisms therefor without the replacement of such mechanisms by other machine parts or mechanisms for closing the needles. Also, the elimination of the presser bar enables eccentrics to be used instead of cams for reciprocating the needles and for actuating the thread-guide bar or bars and the sinker bar. By thus eliminating the presser bar and the actuating cams, hereinbefore referred to, the speed of operation of the knitting machine can be considerably increased.

Pursuant to the present invention, the above results are achieved in a simple way, namely, by the construction and arrangement of the needles which enables the beards thereof to be closed by the tension of the thread supplied to the needles from the thread guides carried by the thread-guide bar or bars. This constitutes another object of the invention.

The invention will be fully understood by those skilled in the art of knitting, from the following description considered in connection with the accompanying illustrative drawings.

In the drawings:

Fig. 1 is a greatly enlarged perspective view of the upper end portion of a needle embodying the present invention;

Fig. 2 is a sectional view on the line 2—2 of Fig. 1;

Fig. 3 is a view illustrating the needle and other parts of a warp knitting machine of the present invention, the machine being of the type in which the needles reciprocate along inclined lines, the needle being illustrated in its position at the start of its downward stroke;

Fig. 4 is a view similar to Fig. 3, illustrating the invention in connection with a knitting machine in which the needles reciprocate in a vertical plane, the needle being similarly illustrated

2

in its position at the start of its downward stroke.

Referring now to the drawings in detail, the needle 10 of the present invention comprises the usual shank 12 and a spring-beard 14 which is provided, as here shown, with a closing member 16. The closing member 16 is in fixed relation to the end 18 of spring-beard 14, said beard 14 and member 16 being preferably integral with each other. Member 16 has one side part 20 which extends longitudinally upwardly from the end of the beard 18 to an upper curved end portion 22 from which the other side part 24 of said member extends longitudinally downwardly, terminating at its lower end 26 at a point preferably slightly above the lower end 18 of beard 14, i. e., near the opening between the end 18 of the beard and the confronting portion of the needle. The upper part of needle 10 which confronts the beard 14 is provided with a groove 28 to receive the end 15 of the beard 14 when the latter is closed in the stitch-casting off operation. As here shown, however, groove 28, the lower part of which corresponds to the beard-receiving groove of the usual needle, extends a substantial distance in 20 the head or beard-confronting part 30 of the needle to a point well above the lower ends 18 and 25 26 of the beard and side part 24 of beard-closing member 16, so that the lower end portion of side part 24 or member 16 is positioned in said groove 30 when the beard is open, as well as when the beard 35 is closed. It will be understood that groove 28 is deep enough to allow free movement of side part 24 of member 16 in said groove, toward and away from the bottom thereof, without engagement of said part of member 16 with the bottom 40 of said groove. Preferably, as here shown, the head 30 of the needle is offset laterally from the median axial line of the needle shank 12, the lateral offset being preferably such that the center 45 of the upper part 22 of member 16 is in alignment with said axial line of the needle shank.

Figs. 3 and 4 of the drawings show a needle 10 in relation to the sinker S and to the thread guides G carried by the thread-guide bars B, respectively, of a warp knitting machine, it being understood that said guide bars are mounted for oscillation as in the usual warp knitting machine. It will be understood that while Fig. 3, and also Fig. 4, shows two guide bars B, the warp knitting machine may be provided with a different number of guide bars, for example, with three guide bars or with only one guide bar. It will be noted that the presser bar usually provided for closing the spring-beard of the needle for the stitch-cast-50 ing operation is eliminated and that the spring-55

beard 14 of the needle 10 of the present invention is closed at the proper time during the downward stroke of the needle 10, by reason of the tension of the thread or threads T on actuating member 16.

It will be understood that the warp knitting machine of the present invention is constructed as heretofore except that, as explained above, the presser bar for closing the beards of the needles and the mechanisms for actuating the presser bar are eliminated. Also, as a result of the present invention, eccentrics may be provided instead of the usual cams for actuating the sinker bar, the needle-carrying bar, and the yarn-guide bar or bars. It will be understood that, as in the usual warp knitting machine, the threads T extend from their respective yarn guides G along the shanks of the companion needles, in position against said shanks, respectively, to the previously knit loops of the fabric (not shown), and that said threads are in engagement with the side parts 24 of the member 16 of the companion needles. It will be understood that the tension of the thread supplied to the needles 10 is transmitted through the beard-closing members 16 of the needles 10, respectively, whereby to move the lower ends 18 of the beards of the needles into the grooves 28 for closing the beards of the needles in the stitch-casting off operation. It will be noted further that by reason of the fact that the side part 24 of beard-closing member 16 extends a substantial distance downwardly from the upper part 22 thereof, the thread supplied to the needle from the companion yarn guide or guides G engages the beard-closing member 16 in proper relation thereto so that the proper force acting in the proper direction is transmitted by the threads to member 16 and by the latter to the lower end 18 of the beard 14 for closing the latter.

While I have shown the preferred embodiment of my invention, it will be understood that various changes in the details of the construction and in the arrangement of parts may be made without departing from the underlying idea or principles of the invention within the scope of the appended claims.

Having thus described my invention, what I claim and desire to secure by Letters Patent is:

1. A needle for a warp knitting machine, said needle having a spring-beard and a beard-closing member operable by the tension thereon of the thread supplied to the needle from the thread-guide of the machine for closing the beard for the stitching-casting off operation, said member being in fixed relation to said beard and having a part spaced laterally of the beard and extending longitudinally of the upper beard-confronting part of the needle to a point near the opening between the lower end of the beard and the shank of the needle.

2. A needle for a warp knitting machine, said needle having a spring-beard and a beard-closing member operable by the tension thereon of the thread supplied to the needle from the thread-guide of the machine for closing the beard for the stitch-casting off operation, said member being in fixed relation to said beard and having a part spaced laterally of the beard and extending longitudinally of the upper beard-confronting part of the needle to a point near the opening between the lower end of the beard and the shank of the needle, said upper part of the needle which confronts the beard thereof having a groove

into which said longitudinally extending part is movably positioned.

3. A needle for a warp knitting machine, said needle having a spring-beard and a beard-closing member operable by the tension thereon of the thread supplied to the needle from the thread-guide of the machine for closing the beard for the stitch-casting off operation, said member being in fixed relation to said beard and having a part spaced laterally of the beard and extending longitudinally of the upper beard-confronting part of the needle to a point near the opening between the lower end of the beard and the shank of the needle, said upper part of the needle which confronts the beard thereof having a groove into which said longitudinally extending part is movably positioned, said groove extending downwardly into the shank of the needle to receive the end of the beard in the closing operation thereof.

4. A needle for a warp knitting machine, said needle having a spring-beard and a beard-closing member operable by the tension thereon of the thread supplied to the needle from the thread-guide of the machine for closing the beard for the stitch-casting off operation, said member being in fixed relation to said beard and having a part spaced laterally of the beard and extending longitudinally of the upper beard-confronting part of the needle to a point near the opening between the lower end of the beard and the shank of the needle, said upper beard-confronting part of the needle being offset laterally from the longitudinal axis of the needle shank.

5. A needle for a warp knitting machine, said needle having a spring-beard and a beard-closing member operable by the tension thereon of the thread supplied to the needle from the thread-guide of the machine for closing the beard for the stitch-casting off operation, said member being in fixed relation to said beard and having a part extending upwardly from the lower end of said beard and a part extending downwardly from the latter in position adjacent the upper beard-confronting part of the needle to a point near the opening between said end of the beard and the confronting portion of the needle.

6. A needle for a warp knitting machine, said needle having a spring-beard and a beard-closing member operable by the tension thereon of the thread supplied to the needle from the thread-guide of the machine for closing the beard for the stitch-casting off operation, said member being in fixed relation to said beard and having a part extending upwardly from the lower end of said beard and a part extending downwardly from the latter in position adjacent the upper beard-confronting part of the needle to a point near the opening between said end of the beard and the confronting portion of the needle, said beard-confronting part of the needle having a groove into which said downwardly extending part is movably positioned.

7. A needle for a warp knitting machine, said needle having a spring-beard and a beard-closing member operable by the tension thereon of the thread supplied to the needle from the thread-guide of the machine for closing the beard for the stitch-casting off operation, said member being in fixed relation to said beard and having a part extending upwardly from the lower end of said beard and a part extending downwardly from the latter in position adjacent the upper beard-confronting part of the needle to a point near the opening between said end of the beard

and the confronting portion of the needle, said beard-confronting part of the needle having a groove into which said downwardly extending part is movably positioned, said groove extending downwardly into the shank of the needle to receive the end of the beard in the closing operation thereof.

8. A warp knitting machine provided with spring-beard needles and thread guides, each of said needles having a beard-closing member operable by the tension thereon of the thread supplied to the needle from the yarn guide therefor, said member being in fixed relation to said beard and having a part spaced laterally of the

beard and extending longitudinally of the upper beard-confronting part of the needle to a point near the opening between the lower end of the beard and the shank of the needle.
